UNITED STATES PATENT OFFICE

121,210

DESIGN FOR A COLOR GUIDE UNIT FOR ARTIFICIAL TEETH

Winfred Lambdin, Philadelphia, Pa., assignor to
Universal Dental Company, Philadelphia, Pa.,
a corporation of Pennsylvania

Application April 10, 1940, Serial No. 91,567

Term of patent 14 years

To all whom it may concern:

Be it known that I, Winfred Lambdin, a citizen
of the United States and a resident of Phila-
delphia, county of Philadelphia, State of Penn-
sylvania, have invented a new, original, and or-
namental Design for a Color Guide Unit for
Artificial Teeth, of which the following is a speci-
fication, reference being made to the accom-
panying drawing, forming a part thereof,
wherein:

Figure 1 is a front elevational view of a color

guide unit for artificial teeth showing my new
design.

Figure 2 is a top plan view thereof;

Figure 3 is an end elevational view thereof;
and

Figure 4 is a perspective view thereof.

I claim:

The ornamental design for a color guide unit
for artificial teeth, as shown.

WINFRED LAMBDIN.
